UNITED STATES PATENT OFFICE

GEORGE E. PRENTICE, OF BERLIN, CONNECTICUT

LOCKING SLIDER FOR FASTENERS

Application filed January 6, 1932. Serial No. 584,994.

This invention relates to separable fasteners of the slider-actuated type and pertains more particularly to an improved slider having provision for locking it in any desired position of adjustment and applicable to fasteners in which the slider is moved either upwardly or downwardly respectively enclosing the gap or opening.

55

In my Patent No. 1,778,338, dated October 14, 1930 I have disclosed one desirable form of double-locking slider in which a friction shoe, independent of the other slider parts, is loosely fitted in a window in the front wing of the slider and is caused to press against the fastener elements by the operation of a cam on the pull tab, thereby frictionally locking the slider in adjusted position. In my copending application, Serial No. 463,930, filed June 26, 1930, I disclosed other arrangements of double-locking slider, one of which differs essentially from the structure shown in my aforesaid patent in omitting the friction shoe and causing the cams on the pull tab to bear directly against the fastener elements. In a second form disclosed in said application, the cams of the pull tab bear directly against the front wing of the slider so as to bend or deflect the latter inwardly against the fastener elements.

50 All of the aforementioned arrangements are practical and commercially useful, but I have also devised an improved arrangement which provides the desired locking action afforded by such prior devices in an even more advantageous manner. In accordance with the present invention I provide a friction shoe preferably so arranged as to distribute the frictional pressure generated by the tab cam over several units of the series, thus avoiding any possible tendency permanently to displace or injure the fastener elements, but so constructed and arranged that the friction shoe constitutes an integral portion of the tab-supporting member of the slider, thus avoiding the cost and trouble of making an independent friction shoe and assembling it with the other parts. In accordance with the present invention the front wing of the slider has a window or opening through which the tab cam projects so that no deflection of the

wing is necessary and the slider body may be made as rigid as is desired for accuracy of operation and durability in use. The present arrangement provides a tab-supporting member which is of resilient yielding character, so that the application of pressure by the tab cam is to a certain extent cushioned, thus avoiding excess strain on the parts and at the same time assisting in retaining the pull tab in locking position.

60 65

In the accompanying drawing in which I have illustrated one desirable embodiment of the invention by way of example:

Fig. 1 is a fragmentary front elevation to large scale of a fastener of the class described, provided with a locking slider embodying the present means;

Fig. 2 is a plan view of a blank suitable for use in making the improved slider;

Fig. 3 is a plan view of the blank of Fig. 2 showing the result of certain of the earlier steps in the operation of forming the slider;

Fig. 4 is a bottom plan view of the slider body before the pull-retaining member has been assembled therewith;

75

Fig. 5 is a vertical section on the line 5—5 of Fig. 4;

Fig. 6 is a plan view of a blank useful in making the pull-retaining member;

Fig. 7 is an edge elevation showing the blank of Fig. 6 after having been bent to form the pull-retaining member;

80

Fig. 8 is a perspective view of the complete slider but with the pull tab broken away;

85

Fig. 9 is a section substantially on the line 9—9 of Fig. 1, showing the slider with the pull tab in locking position;

90

Fig. 10 is a view similar to Fig. 9 but showing a slider arranged for closing the fastener by downward movement, and showing the pull tab in locking position; and

95

Fig. 11 is a fragmentary perspective view of a pull tab of preferred construction.

Referring to the drawing, the fastener here illustrated comprises the flexible stringers 1 and 2 provided respectively with series of fastener elements 3 and 4, which may be of any usual and desirable construction. The fastener units or elements of the opposed

100

series are moved into and out of engagement by means of a slider 5 having the usual convergent channels and operating in a manner well known to those skilled in the art.

5 In accordance with the present invention this slider is preferably made from a piece of sheet material, such as shown in Fig. 2 for example, comprising the portions 6 and 7 adapted to constitute the front and rear wings 10 respectively of the slider, such portions being united by the neck member 8. The blank shown in Fig. 2 is subjected to a series of operations including bending, folding or the like to form a slider body of the desired construction. At an early stage in the process the lateral margins of the members 6 and 7 are turned upwardly to form flanges 9 and 10 (Fig. 3) and the member 6 is provided with an opening or window 11 substantially midway its top and bottom and is preferably furnished with an offset near its lower end providing a positioning recess 12 at its inner surface. The material of the blank is manipulated, to bring the front and rear wing portions into spaced parallel relation and to provide a neck 8^a (Fig. 4), which in accordance with the preferred construction is of substantially tubular form and adapted to hold the front and rear wings rigidly in spaced relation. A slider of this general construction is disclosed in my copending application, Serial No. 562,518, filed September 12, 1931, to which reference may be had for a more detailed description of the shape of the rigid tubular neck and the steps employed in forming the same.

In Fig. 6 I have illustrated a blank useful in forming a unitary part, one portion of which constitutes a pull-retaining member 40 and another portion of which constitutes a friction shoe, said blank preferably consisting of resilient material, usually metal, and comprising an elongate ribbon-like strip 13 recessed to provide a narrow neck 14 adjacent 45 to one of its ends, said neck terminating in a head 15.

The other end of this blank is of greater width than the body portion and this wider part 16 is designed to form the friction shoe 50 for engagement with the fastener element, as hereinafter described. This blank is bent at the point 17 (Fig. 7) to form substantially a right angle and is then bent at 18 to form an outstanding loop portion whose inner surface 55 is adapted to constitute a bearing for the pivot member of the pull tab. At the point 19 the blank is folded substantially double upon itself to form an open U-shaped fold.

The pull tab may be made from sheet metal 60 or other suitable material, and comprises the finger-engaging portion 20 having at its upper end, as viewed in Fig. 11, a pair of cam lugs 21 and 22, integral with the finger-engaging portion and integrally united with one 65 another by the pivot member 23, the latter

preferably being of circular cross section. The two cam lugs are substantially alike and in a preferred construction each cam lug projects symmetrically from the plane of the finger-engaging portion at opposite sides of the latter, so that a vertical section of the pull tab through one of these cam lugs would be of substantially T-shape, the finger-engaging portion forming the upright of the T, and the projecting members of the cam lug forming the cross bar of the T, such projecting portions being indicated in Fig. 9 at 70 21^a and 21^b respectively. The outer ends of these projecting portions are preferably smoothly rounded to form cam surfaces, and 80 preferably the line joining the extreme outer points of these projections 21^a and 21^b would pass slightly above the pivotal axis of the member 23, as viewed in Fig. 9.

Having prepared the pull tab and the part 85 which is to constitute the combined pull-retaining member and friction shoe, the pivot member 23 of the pull tab is disposed within the bearing formed by the bend 18, for example by springing it behind the member 16. 90 The fold 19 of the part which constitutes the combined pull-retaining member and friction shoe is slipped over the lower edge of the front wing of the slider so that its inner ply lies in the recess 12 of the front wing with 95 the part 16 disposed substantially opposite to the window 11 of the front wing, the upper edge of the part 16 being free so that when subjected to pressure the part 16 is readily sprung inwardly against the fastener elements, the resiliency of the material permitting it to flex at the bend 19. The part 14 is then disposed within the trough like fold of the neck (which at this stage is not completed) with the part 15 disposed at the rear side of the slider body. The extreme upper edges of the neck are then pressed inwardly to embrace the neck 14, thus firmly anchoring the upper end of the pull-retaining member to the neck. 100

The assembly of the slider being thus completed, it may be applied to the stringers with their series of fastener elements in the usual manner prior to the application of the end stops to the stringers, such assembly of the slider with the stringers being facilitated by swinging the pull tab substantially at right angles to the plane of the slider body. When assembled, the friction shoe 16 lies between the inner surface of the front wing and the front surfaces of the fastener elements, and it may be noted (Fig. 9) that the friction shoe is of such a size as to bear against several of the fastener elements simultaneously. When, as in Fig. 9, the pull tab is in depending position (and preferably pressed rearwardly into contact with the front wing of the slider) the cam surface at the extremity of the projection 21^a bears 110 against the friction shoe and resiliently 115

120

125

130

presses the latter against the fastener elements, thus firmly locking the slider in position, it being noted that because the pivotal axis of the pivot member 23 lies below the 5 line connecting the extreme points of the cam projections 21^a and 21^b, the parts when positioned, as in Fig. 9, are locked against accidental disengagement, the resiliency of the part constituting the pull-retaining member 10 assisting in securing this locking action.

In Fig. 10 the slider is shown as applied to a fastener which is closed by downward movement and in this arrangement the cam projection 21^b contacts with the friction shoe 15 and locks the slider in the same way as in the arrangement of Fig. 9.

Obviously the pull tab may, if desired, be provided with a cam element or elements on one face only so that it may be employed with 20 a single locking slider, but the advantages of the friction shoe (integrally united with the pull-retaining member and formed of resilient material) are inherent in the structure whether it be a double locking or a single 25 locking slider.

While I have shown my improved locking means as applied to a slider body of a preferred construction I contemplate that it may be utilized with slider bodies of other specific types and that various changes in size, 30 proportion and relative arrangement of parts may be made without departing from the spirit of the invention.

I claim:

35 1. A slider for use with separable fasteners of the kind having opposed series of interengageable fastener elements, said slider having convergent guide channels for the reception of the opposed series and comprising front 40 and rear wings rigidly united by a neck, a part secured at one end to the neck, said part comprising a pull-retaining member having bearing means intermediate its ends, the opposite end of said part constituting a friction 45 shoe disposed for engagement with the fastener elements, and a pull tab provided with a pivot member journaled in said bearing means, said pull tab having a cam portion engageable with said friction shoe in certain 50 positions of the tab and operative to press the shoe into retaining engagement with the fastener means, the front wing of the slider being so shaped as to permit engagement of the cam portion of the tab with the friction 55 shoe.

2. A slider for use with separable fasteners of the kind having opposed series of interengageable fastener elements, said slider having convergent guide channels for the reception of the opposed series and comprising front and rear wings rigidly united by a tubular neck, an elongate part having one end anchored in said tubular neck and comprising a pull-retaining member extending longitudinally of the front wing of the slider,

the opposite end portion of said elongate part being disposed at the inner side of the front wing and constituting a friction shoe adapted to engage the front faces of the fastener elements, said pull retaining member having a forwardly directed bend at an intermediate point constituting a bearing, a pull tab having a pivot member arranged to turn in said bearing, the pull tab having eccentric cam portions adjacent to its pivotal axis, the front wing having a passage through which the cam portions of the pull tab may pass for operative engagement with the friction shoe. 75

3. A slider for use with separable fasteners of the kind having opposed series of interengageable fastener elements, said slider having convergent guide channels for the reception of the opposed series and comprising front and rear wings rigidly united by a neck, a part consisting of an elongate resilient piece of material having one end secured to the neck and comprising a pull-retaining member extending longitudinally of and substantially parallel to the front wing and spaced from the latter, said part having a fold embracing the lower edge of the front wing and having its free end portion disposed at the inner side of the front wing and intermediate the latter and the fastener elements with which the slider is associated, the pull-retaining member having a bearing at a point intermediate the ends of the front wing and the latter having a window opposite said bearing, and a pull tab of substantially T-shape in section comprising a finger-engaging part and opposite cam portions forming the cross bar of the T, said pull tab having a pivot adjacent to the intersection of its cross bar and the finger-engaging portion, the pivot being journaled in the bearing in the pull-retaining member. 105

4. A slider for use with separable fasteners of the kind having opposed series of interengageable fastener elements, said slider having convergent guide channels for the reception of the opposed series and comprising front and rear wings rigidly united by a neck, a pull tab comprising a pivot member, a finger-engaging portion, and a cam, and a resilient part, one portion of which constitutes a friction shoe disposed at the inner side of the front wing of the slider and another portion of which is shaped to provide a bearing disposed at the outer side of the front wing, the pivot member of the pull tab being journaled in said bearing portion, the front wing having an opening through which the cam of the pull tab projects into engagement with the friction shoe. 115

5. A slider for use with separable fasteners of the kind having opposed series of interengageable fastener elements, said slider having convergent guide channels for the reception of the opposed series and comprising front and rear wings rigidly united by a 120

- neck, the front wing having a window therethrough at a point intermediate its ends and having an offset at its lower end providing a positioning recess in its inner surface, an 5 elongate resilient part secured at one end to the neck and extending longitudinally of the front wing and having a fold embracing the lower edge of the front wing, that portion of the fold which is at the inner side of the 10 wing being disposed in the positioning recess of the latter and terminating in a friction shoe arranged opposite the window in the wing, a pull tab having pivotal connection to that portion of said elongate part which lies 15 between the neck and the lower edge of the front wing, and means actuated by the pull tab for pressing the friction shoe against the fastener elements with which the slider is associated.
- 20 6. A slider for use with separable fasteners of the kind having opposed series of interengageable fastener elements, said slider having convergent guide channels for the reception of the opposed series and comprising 25 front and rear wings rigidly united by a neck, an elongate part secured at one end to the neck and comprising a pull-retaining member extending lengthwise of the front wing, the latter having a positioning recess at its 30 lower end, said elongate part having a fold embracing the lower end of the wing and having a portion disposed in said positioning recess with the free extremity of the elongate part disposed between the plane of the inner 35 surface of the front wing and the fastener elements with which the slider is associated, the intermediate portion of the pull-retaining member having a bearing, and a pull tab journaled in said bearing.
- 40 7. A slider for use with separable fasteners of the kind having opposed series of interengageable fastener elements, said slider having convergent guide channels for the reception of the opposed series of fastener elements 45 and comprising front and rear wings rigidly united by a neck, a part secured to the slider, one portion of said part being so constructed and arranged as to constitute a resilient friction shoe extending upwardly from the lower 50 end of the front wing and interposed between the inner surface of the wing and the fastener elements with which the slider is associated, and another portion of said part extending longitudinally of the front wing of the slider 55 and being shaped to provide a bearing for supporting a pull tab, and a pull tab journaled to turn in said bearing about an axis extending transversely of the length of the slider, said pull tab comprising a cam member, the front wing being so shaped as to permit engagement of the friction shoe by said cam member.
- 60 8. A slider for use with separable fasteners of the kind having opposed series of interengageable fastener elements, said slider 65 having convergent guide channels for the reception of the opposed series and comprising front and rear wings rigidly united by a neck, the front wing having a window at a point intermediate its ends, an elongate strip of resilient material secured at one end to the neck and having an outward bend at a point substantially opposite said window, the inner surface of said bend constituting a bearing, a pull tab journaled in said bearing, the pull tab having a cam element disposed to project through said window, the resilient strip being arranged to extend downwardly and around the lower end of the front wing and having a widened portion arranged at the inner side of the front wing and substantially opposite said window, said widened portion constituting a friction shoe and being of a size such as to engage a plurality of fastener elements simultaneously. 70
- 75 9. A slider for use with separable fasteners of the kind having opposed series of interengageable fastener elements, said slider having convergent guide channels for the reception of the opposed series and comprising front and rear wings rigidly united by a neck, the front wing having an opening therethrough at a point substantially midway between its top and bottom, a part comprising a resilient friction shoe disposed at the inner side of said front wing and opposite said opening, said shoe being of a size such as simultaneously to engage a plurality of fastener elements, said part having, in integral continuation of 80 said shoe, a pull-retaining member disposed at the outer side of the wing, said pull-retaining member having a bearing at a point opposite the window, and a pull tab having a pivot member disposed in said bearing, said pull tab comprising a finger-engaging portion and cam members projecting substantially symmetrically at opposite sides of the plane of the finger-engaging portion, said cam members being arranged for alternative engagement with the friction shoe. 85
- 90 10. A slider for use with separable fasteners of the kind having opposed series of interengageable fastener elements, said slider having convergent guide channels for the reception of the opposed series and comprising front and rear wings rigidly united by a neck, a pull tab having a pivot member, an elongate strip of material secured at one end to the neck and comprising a pull-retaining member extending longitudinally of the front wing in substantially parallel spaced relation thereto, said pull-retaining member having an outward bend embracing the pivot member of the pull tab and forming a bearing for the tab, said strip of material having a fold embracing the lower edge of the front wing, the latter having a recess in its inner face for positioning the inner ply of the fold, said inner ply being resilient and constituting a friction shoe engageable with the fastener 95 100
- 100 110 115 120 125 130

elements, and means carried by the pull tab for pressing said shoe against the fastener element.

11. A slider for use with separable fasteners of the kind having opposed series of interengageable fastener elements, said slider having convergent guide channels for the reception of the opposed series and comprising front and rear wings rigidly united by a neck, a pull tab consisting of an integral piece of material comprising a finger-engaging portion, a pair of spaced cam lugs, a pivot member of circular section integrally uniting the cam lugs, the cam lugs projecting outwardly from opposite faces of the finger-engaging portion and having cam surfaces at their outer ends, and pull supporting means mounted on the slider and provided with a journal bearing for said pivot member.
12. A slider for use with separable fasteners of the kind having opposed series of interengageable fastener elements, said slider having convergent guide channels for the reception of the opposed series and comprising front and rear wings rigidly united by a neck, a pull tab consisting of an integral piece of material comprising a finger-engaging portion, a pair of spaced cam lugs and a pivot member integrally uniting said lugs, the cam lugs projecting outwardly from one face at least of the pull tab and having cam surfaces at their outer ends, and bearing means carried by the slider, said bearing means being disposed adjacent to the front face of the front wing and providing a journal bearing for said pivot member.
13. A slider for use with separable fasteners of the kind having opposed series of interengageable fastener elements, said slider having convergent guide channels for the reception of the opposed series and comprising front and rear wings rigidly united by a neck, a pull tab consisting of an integral piece of material comprising a finger-engaging portion, a pair of cam lugs, and a pivot member integrally uniting said cam lugs, the pivot member being of substantially circular cross section, the cam lugs projecting outwardly from opposite faces of the finger-engaging portions and having cam faces whose outermost points are disposed in a plane spaced from the pivotal axis of the pivot member and an elongate part comprising a pull supporting member extending downwardly from the neck along the front of the front wing, said pull supporting member providing a pivotal support for the pull tab.

Signed by me at Berlin, Connecticut, this fourth day of January, 1932.

GEORGE E. PRENTICE.
